CLAIM

The ornamental design for a frame of a gokart, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front isometric view of a frame of a gokart.

FIG. 2 is a front elevation view thereof.

FIG. 3 is a back elevation view thereof.

FIG. 4 is a left side elevation view thereof.

FIG. 5 is a right side elevation view thereof.

FIG. 6 is a top plan view thereof.

FIG. 7 is a bottom view thereof.

FIG. 8 is a back isometric view thereof.

FIG. 9 is a front isometric view of a second embodiment of a frame of a gokart.

FIG. 10 is a front elevation view thereof.

FIG. 11 is a back elevation view thereof.

FIG. 12 is a left side elevation view thereof.

FIG. 13 is a right side elevation view thereof.

FIG. 14 is a top plan view thereof.

FIG. 15 is a bottom view thereof.

FIG. 16 is a back isometric view thereof.

FIG. 17 is a front isometric view of a frame of a gokart in a folded configuration.

FIG. 18 is a front elevation view thereof.

FIG. 19 is a back elevation view thereof.

FIG. 20 is a left side elevation view thereof.

FIG. 21 is a right side elevation view thereof.

FIG. 22 is a top plan view thereof.

(Continued)

FIG. 23 is a bottom view thereof; and,
 FIG. 24 is a back isometric view thereof.
 The solid background color in the figures is intended to show
 contrast with the light and dark surfaces of the claimed
 design and forms no part of the claim.
